UNITED STATES PATENT OFFICE.

IRWIN M. KROHN AND MICHAEL J. SULLIVAN, OF CINCINNATI, OHIO.

SHOE.

1,282,874.

Specification of Letters Patent. Patented Oct. 29, 1918.

Application filed March 28, 1916. Serial No. 87,335.

To all whom it may concern:

Be it known that we, IRWIN M. KROHN and MICHAEL J. SULLIVAN, citizens of the United States, and residing at Cincinnati, 5 in the county of Hamilton and State of Ohio, have invented a new and useful Improvement in Shoes, of which the following specification is a full disclosure.

Our invention relates to a new and improved 10 shoe having a cover for the outer heel surface nailed to the lasted shoe parts above the uppermost heel surface.

The preferred method of producing or forming this article is fully disclosed and 15 claimed in our application Serial No. 76,547, filed February 7, 1916.

One of the objects of the invention is to provide a shoe having a covered heel, preferably of the lift-type, wherein the upper 20 margin of the heel cover is secured to the lasted heel seat portion of the shoe above the heel, said margin preferably being nailed directly to the heel margin of the upper, the other portion of the cover being secured 25 upon the outer heel surface. The features of the invention will be more fully set forth in connection with the description of the accompanying drawings forming a part of this specification, wherein,

30 Figure 1 is a perspective view of the shoe showing the heel covered.

Fig. 2 is a similar view showing a heel in section and the outsole and upper in partial section.

35 Fig. 3 shows a sectional view through a shoe with a lift-type heel constituting the preferred form.

Fig. 4 shows the heel cover secured to the lasted heel seat, and folded over the sides 40 of the last, before the outsole is laid.

The heel 7 may be solid, as indicated in Fig. 2, or sectional or lift-type, as shown in Fig. 3.

45 The heel cover 1 is adhesively secured to the outer heel surface, the term "outer heel surface" being used to contra-distinguish from the breast portion of the heel which forms an angle with the outsole on the bottom of the shoe.

50 In the lift-type of heel shown in Fig. 3, this cover 1 conceals the lift-joints indicated by the lines 8—8, no heel burnishing step being necessary.

The upper material 4 at the heel of the 55 shoe is bent over the heel of the last forming the upper heel margin 3 on the heel portion

of the bottom of the last, that is to say, the surface 3 is the conventional heel seat. The outsole 5 is laid, as usual, and secured to the previously lasted upper portions of the shoe, 60 the outsole having a heel margin 2 covering the heel seat 3 and upon which the heel is built. The heel cover 1 has a heel seat margin 16 inturned over the heel of the last and held between the adjacent heel margin 65 surfaces of the upper and outsole, being preferably nailed directly to the heel margin of the upper by nails 17 before the outsole is laid and secured to the lasted upper.

That is to say, the heel cover margin is 70 lasted upon the heel seat of the shoe, so that the heel of the outsole contacts this heel cover margin instead of the heel seat of the upper, or this margin of the heel cover may be regarded as the ultimate heel seat, since 75 it is secured to the upper, and smooth and flat, and forms the direct seat for the heel portion of the outsole.

Preferably, also, the heel end of the 80 outsole is forwardly skived to form the flap 6 for covering the breast of the heel, the forward free edges of the heel cover 1 being preferably adhesively secured directly upon the heel breast and covered by the outsole breast flap 6. The unattached portion of the 85 heel cover is adhesively secured upon the outer heel surface extending contiguously with the heel portion of the upper 4, the heel seat edge of the outsole extending flush with the outer heel surface and being concealed under said heel cover, this concealed joint formed between the uppermost heel surface and the heel margin of the outsole being indicated by dotted lines 5 in Fig. 1.

The heel seat margin 16 of the cover is 90 preferably nailed directly to the heel margin 3 of the upper before the outsole is laid, providing a good heel seat for the heel of the outsole, thus enabling a lift type heel to be built on the heel of the outsole, the 100 outsole heel being really the top lift of the heel structure. This lift-type heel is shown in Fig. 3, wherein the first heel section 9 (made of lifts) is laid on the outsole heel seat and secured by nails 11, the bottom 105 section 10, being secured thereon by nails 12. The bottom heel lift 13 is secured by nails 14, the covering preferably terminating at the bottom lift-joint.

A shoe so constructed is strong, durable 110 and comfortable and more ornamental, the heel-lift joints and the heel seat edge of the

outsole being concealed under the cover selected to harmonize with the entire ornamental plan of the shoe. Also, one portion of the cover being secured to the outer heel 5 surface, and the other portion being nailed directly to the heel margin of the upper, forms a tie structurally uniting the heel directly to the heel seat portion of the upper, the heel, of course, being additionally 10 secured by nails to the heel of the outsole.

Having described our invention, we claim:

1. In a shoe, an upper and heel in combination with a heel covering marginally secured to the heel seat margin of the upper 15 by a row of tacks, having their heads disposed between the heel covering margin and heel.
2. In a shoe, an upper and heel in com-

bination with a heel covering, adapted to inclose the outer surface of the heel and 2 having a marginal lap extending between the joint of upper and heel and secured to the heel seat margin of the upper, and fastening means connecting said covering lap and heel seat margin of the upper, distinctive of the means for securing said upper and heel.

In witness whereof, we hereunto subscribe our names as attested by the two subscribing witnesses.

IRWIN M. KROHN,
MICHAEL J. SULLIVAN.
